FRANZ REINHARDT, OF WALTERSHAUSEN, GERMANY, ASSIGNOR TO FIRM KÄMMER & REINHARDT A. G., OF WALTERSHAUSEN, GERMANY.

SLEEPING DOLL.

1,412,670.

Specification of Letters Patent. Patented Apr. 11, 1922.

Application filed March 29, 1916. Serial No. 87,479.

(GRANTED UNDER THE PROVISIONS OF THE ACT OF MARCH 3, 1921, 41 STAT. L., 1818.)

To all whom it may concern:

Be it known that I, FRANZ REINHARDT, a subject of the German Emperor, residing at 36 Bahnhofstrasse, Waltershausen, in the 5 Duchy of Gotha, in the German Empire, have invented certain new and useful Improvements in Sleeping Dolls, of which the following is a specification.

The object of my invention is to provide 10 means whereby the eyes of a sleeping doll may be kept open or be reopened in a lying position of the doll.

Various devices are known which cause a closing of the eyes of sleeping dolls when 15 these are laid down. In order to approach natural conditions as near as possible it is desirable that such sleeping dolls should keep their eyes open also in a lying position. For this purpose devices have been proposed, 20 by means of which the eyes may be opened and closed from the outside by pulling a string or actuating a lever; in other devices a movable stop may be actuated from the outside by means of a knob or the like, so 25 that said lug locks the weighted lever.

Still further devices are known, which allow of laying a doll down, keeping the eyes open. In these devices the locking means 30 may be released by intermittent or step by step movements of the doll, so that the eyes again become free to move. Such devices, however, require a certain skill or exercise in the use of the doll and by their jerking movement they frequently damage the delicate 35 eye-mechanism.

The object of my invention is to avoid these inconveniences in providing means whereby the parts for locking or releasing the eyes or lids are automatically actuated 40 in a simple, secure and gentle way by turning the doll from one side to the other.

Referring to the accompanying drawings: Fig. 1 is a vertical section through a doll's head according to my invention; Fig. 2 is 45 a back view, the weight being left away; Fig. 3 is a cross-section; Figs. 4 and 5 are back views of other forms of my invention; Figs. 6 to 8 are further forms of my said invention in various views.

50 *a* is the doll's head in the interior of which are the eyes *b*, pivotally arranged on the ends

c of a wire hoop or yoke *e*, supported by eyelets *d*. Acting on the wire yoke *e* is a spring *f*, tending to keep the eyes in constant engagement with the eye openings in the head. 55 Suspended from the top *g* of the head is a weight *h* which is attached to the cross bar *i* connecting the two eyes and which causes the eyes *b* to turn. Pivots arranged above the movable eyes are the eye lids *l*, connected with each other by a stay or bridge *k*. For this purpose, the eye lids *l* are supported by means of a cylindrical part *m* in a ring *n* of the head. To the cylindrical part or drum *m* is fixed a weight *o*, which moves back- 60 wards and thus closes the eye lids when the doll is laid down. 65

Sideways of the weight or pendulum *o* is fixed in the doll's head *a* a sleeve *p*, having inside a loosely fitting pin *q* which can freely 70 slide in the sleeve. A cross pin *r* fixed to the pin *q* and guided in a slot *s* of the sleeve *p* limits the inward and outward movements of the pin *q*.

When the doll is turned over to the right, 75 the pin *q* automatically slides out of the sleeve *p* and locks the rod of the pendulum *o*, thus preventing this pendulum from swinging. Therefore, when the doll is turned or laid on its right side, the eyes will remain 80 open also in the lying position. If the doll is intended to again have a sleeping position, it only wants turning over onto its left side. The pin *q* then slides back, releases the pendulum *o* and consequently also the eye lids. 85

As shown in Fig. 4, the member locking the pendulum *o* may also consist in a pivotally arranged lever *t*, having a weight *u* fixed to its lower end. When turning the doll to the right, the weight *u* causes the lever *t* to 90 adopt the position shown in dotted lines and to lock the pendulum *o* which closes the eye lids or brings about the sleeping condition. In this case also a pivotally arranged stop may be provided on each side of the pendulum.

In the form shown in Fig. 5 two fixed stops *v* are provided at the sides of the pendulum *o* inside of the doll's head. This pendulum *o* is suspended by means of an eyelet *w* to the 100 pivotal bridge *k* of the eye lids in such a way, that it may not only swing forward and

backward, but also move somewhat sideways, as shown in dotted lines in Fig. 5. The ends of the flat stops v facing the pendulum o are turned up to form hooks x . When the doll is laid on the one or the other side, the pendulum swings slightly to one side and gets caught in the hook-shaped end of the respective stop. Therefore the pendulum will be prevented from swinging out into the position corresponding to the closed eye lids. If the doll is laid down on its back the pendulum o can freely swing and pass between the two fixed stops v , thus bringing about the sleeping condition.

15 The stops may also be designed in many other ways. For instance the fixed stops could also be made of wire.

With the devices referred to above and in cases when the doll is laid on the side with 20 closed eyes, so that the locking pin projects out of the sleeve, this locking pin may prevent the mechanism of the sleeping eyes from acting, so that the eyes will not open.

This can be avoided by providing the movable pendulum with a stop which prevents the action of the locking member as for instance the movement of the locking pin into the locking position when the doll is in an unsuitable position.

30 Fig. 6 shows a side view of this form of my invention in connection with a section through the doll's head and Figs 7-8 show two plan views with the respective parts in various positions.

35 The pendulum o is provided with an arc-shaped plate o^1 and as shown in Fig. 7, the locking pin q engages the edge of said plate when the eyes of the doll have to remain open.

40 But, as further shown in Fig. 8 this plate o^1 prevents the pin from sliding out of its sleeve and from locking the pendulum in an unsuitable position of the doll as in such case the pin strikes against the lateral surface of the plate o^1 and is prevented from locking the pendulum.

The position and the form of the plate o^1 depends on the design of the devices causing the movements of the eyes or the lids and the 50 drawing only shows one example of this device.

I claim as my invention:

1. In a doll's head, eyes in the head, eyelids for said eyes, a pendulum for operating the eyelids, and means for automatically controlling the movement of the pendulum to cause it to open or close the eyelids according to the position of the head.

2. In a doll's head, eyes in the head, 60 movable eyelids for the eyes, a pendulum for operating the eyelids, a sleeve in the head and having an open end, and a pin freely slideable in the sleeve and adapted to move by gravity in the path of the pendulum when the doll is turned on one side.

3. In a doll's head, eyes in the head, movable eyelids for the eyes, a pendulum for operating the eyelids, a sleeve in the head and having an open end, a pin freely slideable in the sleeve and adapted to move by gravity in the path of the pendulum when the doll is laid on one side, and a stop secured to the pendulum for controlling the movement of said pin.

4. In a doll's head, eyes for said head, 75 separate eyelids for said eyes, means for moving said lids over said eyes, and means for preventing said movement of said lids until the head has been tilted to one side.

5. In a doll's head, a pair of eyes therefor 80 and a lid for each of said eyes, a movable member actuated by gravity when the head is laid down for actuating said lids in order to close the same, and gravity actuated means for preventing the first mentioned 85 means from operating until the head has been turned to one side.

6. In a doll's head of the character described, eyes in said head, eyelids for said eyes, a pendulum connected with said lids 90 for causing the same to close, said pendulum being mounted to move when the head is laid in a horizontal plane, and means movable transversely to said pendulum under the action of gravity for preventing said 95 pendulum from operating until the head has been rolled to one side.

7. In a doll's head of the character described, eyes arranged in said head, eyelids for covering said eyes, a rotatable member 100 for supporting said eyelids, means acting under gravity for rotating said rotatable member for closing said eyelids when the head is laid in a horizontal plane, and automatically acting means for preventing the 105 first mentioned means actuating said rotatable member until the head has been rocked back and forth.

8. In a doll's head of the character described, eyes arranged in said head, eyelids 110 for said eyes, a movable member for supporting said eyelids, a pendulum connected with said movable member, said pendulum being actuated by gravity when the head is laid in a horizontal plane with the face 115 uppermost, and a sliding weight movable transversely of the pendulum, said sliding weight being arranged to hold the pendulum against movement until the head has been moved to one side so that the weight may move away from the pendulum under the action of gravity whereby the eyelids will close the eyes after the head has been laid down.

9. In a doll's head of the character described, eyes in said head, eyelids for closing the opening in front of the eyes, a rotatable member connected with said eyelids and arranged to move the eyelids to a closed or open position, a pendulum connected with 125

said rotatable member, said pendulum acting under gravity for opening and closing the eyelids according to the position of the head, and a transversely movable weight arranged in the head and acted on by gravity whereby when said head is in one position said pendulum will be pre-

vented from operating and when moved to the opposite position said pendulum will be free to operate.

In testimony whereof, I have signed my name to this specification.

FRANZ REINHARDT.
